UNITED STATES PATENT OFFICE.

ROBERT HAGER, OF ST. LOUIS, MISSOURI.

FIRE-STARTING ELEMENT.

1,366,258.

Specification of Letters Patent. Patented Jan. 18, 1921.

Application filed December 12, 1919. Serial No. 344,385.

To all whom it may concern:

Be it known that I, ROBERT HAGER, a citizen of the United States, residing at St. Louis, in the State of Missouri, have invented new and useful Improvements in Fire-Starting Elements, of which the following is a specification.

This invention relates to a fire starting element and has for its primary object the construction of an element that is capable of starting a coal fire without the necessity of first starting a wood fire and in such a manner that it will not be necessary to have an object permanently lodged within the fire.

An object of the invention is to provide an element entirely of combustible material capable of burning through a length of time great enough to completely ignite the coal.

20 A feature of my invention is the construction of an element with a draft space so that the same will be completely consumed and during its consummation give forth a very large flame.

25 With these and other objects in view the invention will be better understood from the following detailed description taken in connection with the accompanying drawing wherein—

30 Figure 1 is a side elevation of the element with a portion of the covering removed.

Fig. 2 is a vertical sectional view.

Fig. 3 is an elevation of the block.

35 Fig. 4 is an elevation of the spacing member.

Again referring to the drawing illustrating one manner in which my invention may be constructed #1 designates a frame, which in this particular instance is composed of a body portion 2 of wood and a cardboard top

40 3. Supported within the frame is a spacing member 4 composed of combustible material and of a shape to provide a draft space 5

the length of the frame. supported upon the member 4 is a block six of combustible material, which in practice may be waste saturated with an inflammable liquid and compressed so as to burn for a relatively long time. Of course this block can be made of other materials.

If found advantageous in practice the entire element may be inclosed in a covering 7 to hold the parts in their associated relation. This covering may be of mosquito netting impregnated with an inflammable material such as paraffin.

From the foregoing description it will be seen that I provide an element that will be completely consumed, burning for a considerable length of time and besides properly position the combustible members so that air can obtain proper access thereto.

It is, of course, to be understood that the element may be constructed in various other manners and the parts associated in different relations and besides certain parts, if found advantageous, may be constructed of non-inflammable material, and therefore, I do not desire to be limited in any manner except as set forth in the claim hereunto appended.

Having thus described my invention what I claim is—

A fire starting element comprising a combustible frame open on two sides, a compressed block of inflammable material, a spacing member supporting the material spaced from the bottom of the frame to form a draft opening the length of the frame, and a covering of inflammable material for said frame, said material, frame and covering being impregnated with an inflammable liquid.

In testimony whereof I affix my signature.

ROBERT HAGER.
